UNITED STATES PATENT OFFICE.

JAMES MILNOR HICKS, OF SUMMIT, NEW JERSEY, ASSIGNOR TO THE
AUTO STOPPER COMPANY, OF NEW YORK, N. Y.

SEALING-CAP FOR VESSELS.

No. 807,380.

Specification of Letters Patent.

Patented Dec. 12, 1905.

Application filed March 15, 1905. Serial No. 250,192.

To all whom it may concern:

Be it known that I, JAMES MILNOR HICKS, a citizen of the United States, residing at Summit, Union county, New Jersey, have invented 5 certain new and useful Improvements in Sealing-Caps for Vessels, of which the following is a specification.

My invention relates to sealing-caps for vessels and to means for removing the same 10 after the said caps have been locked over the vessel-mouth; and it consists in a certain construction of cap in combination with the vessel to which it is applied, all of which is fully specified and claimed in the following specification.

In order that persons skilled in the art to which my invention appertains may understand, construct, and use my invention, I will proceed to describe it, referring to the accompanying drawings, forming part of this specification, in which—

Figure 1 is a part longitudinal central section and part elevation of a bottle having my invention applied to it and showing a lifter in place ready to grasp the cap for removal. Fig. 2 is a bottom or reversed view of my cap as seen looking upward from the lower side thereof. Fig. 3 is a side view of the cap before it is applied to the bottle. Fig. 4 shows 25 an alternative construction of cap to Fig. 3.

A is the body of the bottle.

B is the exterior of the bottle-neck.

C is a bead on the exterior of the bottle-neck near its top.

D is the top surface of the bottle-sealing cap. D' is a flange pendent from said top surface, but below the bead at the outer diameter of said top surface D. E is said bead.

K is a recessed portion in flange D' at its 30 top, Fig. 4.

F is a stopper located in the mouth of the bottle below the top surface of the cap.

G is the handle.

H and I are the grips of a lifter by which 45 the cap is removed.

The operation of removing the cap from the bottle after it has been locked to the bottle will be readily understood.

The cap and bottle and locking means are 50 similar to that shown in the patent to James

M. Hicks, dated February 21, 1905, No. 783,038; but my present invention consists in providing a means at the top of the cap-flange of the cap by which a lifter for removing the cap may take instead of gripping the lower 55 part of the pendent flange. I avoid by this means the danger met with in other methods of removing the cap of breaking the bead upon the bottle-neck.

It will be seen that the flange of my cap in 60 Fig. 3 represents it as partially finished as to its final shape and before the final shaping in applying it to the bottle, while Fig. 1 shows it in its final shape after its application to the bottle, having the pendent flange D' curved 65 in straining it over the bead on the bottle-neck, as set out in the patent before cited.

I am aware that a simple cup-shaped cap with bead surrounding the top surface is old. Therefore I do not claim broadly such a structure; but what I do claim is a cap provided 70 with means at the upper part of the pendent flange of the cap by which a lifting-tool may take to remove the cap, the pendent flange having a curvilinear shape, as shown in Fig. 1. 75

I have shown in the drawings a bead surrounding the top surface of the cap as the means for affording a gripping edge or projection whereby a lifting-tool may engage with it; but the bead need not in all cases entirely surround the top surface of the cap, and, furthermore, an indentation K may be made in the upper part of the pendent flange for the same purpose and is an equivalent means to that shown in the drawings. It is 80 illustrated in Fig. 4. In deep caps this is the preferred form.

Having now fully described my invention and the manner in which I have embodied it, what I claim as new and as my invention, and 90 desire to secure by Letters Patent, is—

A sheet-metal cap for a vessel, having a flat top surface, a downwardly-trending flange, beneath said top surface, a circumferential flange as an extension of said flat top surface, said 95 flat top surface and flange being of larger diameter than the said downwardly-trending flange, whereby when the said cap is on a vessel the under part of the circumferential flange is above the top of the walls of the vessel and 100

the downwardly-trending flange grips the under side of the bead upon the vessel-neck by virtue of the elasticity of the metal of the flange, in combination with a vessel having a neck and a bead surrounding the neck near the top thereof, all arranged to operate as and for the purposes specified.

5 In testimony whereof I have signed my

name to this specification, in the presence of two subscribing witnesses, this 1st day of 10 March, 1905.

JAMES MILNOR HICKS.
